DISPENSER FOR DELIVERING A SERIES OF INDIVIDUAL CONTAINERS AT ONE TIME

Albert F. Miller, Flushing, N. Y., assignor to Lily-Tulip Cup Corporation, New York, N. Y., a corporation of Delaware

Application October 1, 1948, Serial No. 52,352

4 Claims. (Cl. 214—8.5)

1

This invention relates to container dispensers for delivering during each operating cycle a plurality of individual containers spaced apart in a linear series.

The invention has proven especially useful in delivering paper cups and the like frustro-conical containers in a linear series such as during the waxing operation of said containers, and this embodiment will be described as illustrative of the invention.

In this type of operation it is highly desirable to have the dispenser mechanism as simple and sturdy as possible; as it is in operative connection with very costly apparatus for dipping the containers in molten wax or other liquid proofing material, and thereafter draining the excess wax and then drying the coating remaining on the containers. Hence a failure of the dispensing mechanism will interfere with or cause the shutdown of extensive and expensive equipment and otherwise interfere with production. Likewise it is highly desirable that the dispensing mechanism be adapted to handle a given size of a wide range of sizes of containers with a minimum of adjustment and changes. These are among the important requirements which it is an object of this invention to provide.

This invention consists in the novel features, arrangements and combination of parts embodied by way of example in the apparatus hereinafter described as illustrating a preferred form of the invention, and the invention will be more particularly pointed out in the appended claims.

Further objects, features and advantages of the invention will appear from the following specification and claims, taken in connection with the accompanying drawings, in which:

Fig. 1 is a plan view showing the present embodiment of the invention;

Fig. 2 is a side elevation, partly in section, taken on the line 2—2 of Fig. 1;

Figs. 3 and 4 are segmental plan views of the invention shown in Fig. 1 and illustrating adjustable features of the invention adapting it to containers of different sizes;

Fig. 5 is a somewhat enlarged plan view showing further details of the dispensing unit of Fig. 1;

Fig. 6 is a cross-sectional view taken at 6—6 of Fig. 5 showing further features of the dispensing unit;

Fig. 7 is a segmental view of parts of the dispensing unit shown in Fig. 6 in a different position of operation; and

Figs. 8 and 9 are somewhat diagrammatic views

2

illustrating two steps in the cycle of operation of the dispensing unit.

Referring more particularly to Figs. 1 and 2: a supporting frame is represented by the transversely extending members 10 and 11 which are spaced apart in a longitudinal direction. Plate member 12 is supported by said frame by having its opposite ends rigidly but removably secured to the respective members 10 and 11 as by the bolts 13—14. This member is provided with a plurality of dispensing throats, such as 15, in the present embodiment being ten in number; it being noted that the throats 15 thus provided are spaced apart longitudinally of the member 12 along a common axis. Preferably guide rods, such as 17, are disposed in groups adjacent the throats 15 to hold stacks of containers, such as 8, in vertical alignment therein. A pair of longitudinally extending bars 18—19 are disposed on respectively opposite sides of the guide plate 12 and are adjustably secured adjacent their respectively opposite ends to the support cross members 10—11 by bolts, such as 20, which pass through cooperating holes in the members 18 and 19 and through slots, such as 21, provided in the frame members 10—11.

A series of identical dispensing segments, such as 22, equal in number to the dispensing throats 15, are pivotally mounted for oscillating movement upon pivot bolts, such as 23 (Figs. 5 and 6); the bolts 23 each being provided with a journal portion 24 passing through the outer end of corresponding segments 22 and providing a shoulder engaging the under surface of the plate 12, with the threaded portion of the bolt of reduced diameter passing upwardly through the plate 12 and engaged by a nut 25. Each dispensing segment 22 is provided with an arcuate cam portion comprising a wedge-shaped cam section 26 and a dwell section 27 (Figs. 5 and 8): the cam section 27 when in position as shown in Fig. 8 serving to hold a stack of cups in position with the cam portion 26 serving to separate the lowermost cup A from the stack while retaining the next cup B and the remaining cups of the stack in position (Fig. 9) in the manner well understood by those skilled in the art. A second and similar series of identical dispensing segments, such as 22, are pivotally mounted on bolts, such as 23, and are supported from the member 19 in a manner identical with that previously described with respect to the series of segments supported on the opposite member 18. The arrangement of the parts being such that a pair of oppositely disposed dispenser members 22 have their inwardly

disposed cam faces overlapping respectively opposite sides of the throats 15 adjacent the bottom or outlet thereof and the pivotal axes of the segments 22 being disposed on a line passing through the center of said orifice.

The series of dispenser segments 22 which are mounted on the bar 18 are pivotally connected intermediate their outer ends and inner cam surfaces to an actuating link 28 (Figs. 5 and 6) by means of pivot bolts such as 28a; whereby 10 upon longitudinal reciprocation of the link 28 the segments, such as 22, are caused to oscillate about their pivotal axes 23. Likewise an identical driving link 29 is pivotally attached to the series of dispenser segments 22 mounted on the bar 19. Corresponding ends of the links 28 and 29 are preferably articulated as at 30 and 31, respectively, to outer link ends designated respectively 32 and 33 so as to provide for slight angularity of the outer ends of the driving linkage. The outer ends of the link portions 32 and 33 are pivotally connected to corresponding ends of the respective bell cranks 34-35 which are pivotally mounted at 36-37 on, and carried by, the respective bars 18 and 19. Corresponding other ends of the cranks 34-35 are engaged by pivot bolts 38-39 which are adjustably secured to the driving link 40 as by means of the respective slots 41-42 provided in the link 40. It will therefore be seen that upon reciprocation of the common driving link 40 in a transverse direction the links 18-19 are simultaneously and correspondingly moved in a longitudinal direction, causing the simultaneous oscillation of both sets of dispenser segments 22 and thereby simultaneously dispensing the bottommost cup from the plurality of stacks S of cups. In the present embodiment the machine is shown adapted to dispense a plurality of individual cups C (Fig. 2) in a linear series on a conveyor. To illustrate such use a conveyor member 45 is shown carrying a plurality of studs or vertically extending pins 46 which are to receive the said series of cups when dispensed and convey the same to a position out of alignment with the dispensing units, at which time a second series of studs 46 is moved into position to receive the next series of cups.

Referring more particularly to Figs. 3 and 4, the facility of adjusting the device so as to handle any selected size of container will now more particularly be pointed out. Fig. 3 shows a segment of the device in its position for dispensing the smallest cup for which it is intended, the parts being designated as shown in Fig. 1. When it is desired to dispense a larger size container the guide plate 12 is removed by withdrawing the bolts, such as 13-14. The bolts, such as 20, and the bolts 38-39 are then loosened so as to permit further separation in a transverse direction of the guide bars 18-19 to the position shown in Fig. 4; the lateral spacing apart of the guide bars 18-19 being sufficient to accommodate a new guide plate designated 12a in which the dispensing throats designated 15a are of the required diameter to accommodate the larger size containers. The plate 12a is then rigidly secured in position on the frame, the bars 18 and 19 are moved into contact with the opposite sides of plate 12a and the bolts, such as 20, are fastened into position on the frame members and the driving link 40 is secured in adjusted position to the crank arms 34-35 by tightening the pivot bolts 38-39. This adjustment automatically places the cam portions in the proper operative position previously described.

Having thus described my invention with particularity with reference to its preferred form, it will be obvious to those skilled in the art, after understanding my invention, that other changes and modifications may be made therein without departing from the spirit and scope of my invention, and I aim in the appended claims to cover such changes and modifications as are within the scope of the invention.

What I claim is:

1. In a dispensing mechanism for delivering a plurality of containers in a linear series, the combination of end supports, a pair of substantially parallel longitudinally extending laterally spaced rails having their ends secured to said supports, a longitudinally extending throat member disposed in the space between said rails and having its ends secured to said end supports, said throat member being provided with dispenser throats extending therethrough in spaced relation along a longitudinal axis, two series each comprising a plurality of dispenser segments individually pivotally mounted adjacent their outer ends on said rails for angular movement in a horizontal plane and provided on their inner ends with arcuate cam portions, the segments of one series being disposed opposite the segments of the other series to provide pairs of segments whose cam portions when moved about their pivotal axes move across the opposite edges of respectively cooperating throats to thereby engage the lowermost containers of stacks disposed in said throats, and a common drive train operatively connected to said segments of said two series for simultaneous actuation thereof, whereby a linear series of containers may be dispensed simultaneously.

2. In a dispensing mechanism for delivering a plurality of containers in a linear series, the combination of end supports, a pair of substantially parallel longitudinally extending laterally spaced rails having their ends adjustably secured to said supports for varying the lateral spacing of said rails, a longitudinally extending throat member disposed in the space between said rails and having its ends removably secured to said end supports, said throat member being provided with dispenser throats extending therethrough in spaced relation along a longitudinal axis, two series each comprising a plurality of dispenser segments individually pivotally mounted adjacent their outer ends on said rails for angular movement in a horizontal plane and provided on their inner ends with arcuate cam portions, the segments of one series being disposed opposite the segments of the other series to provide pairs of segments whose cam portions when moved about their pivotal axes move across the opposite edges of respectively cooperating throats to thereby engage the lowermost containers of stacks disposed in said throats, and a common drive train operatively connected to said segments of said two series for simultaneous actuation thereof, whereby a linear series of containers may be dispensed simultaneously.

3. In a dispensing mechanism for delivering a plurality of containers in a linear series, the combination of end supports, a pair of substantially parallel longitudinally extending laterally spaced rails having their ends adjustably secured to said supports for varying the lateral spacing of said rails, a longitudinally extending plate disposed in the space between said rails and having its ends removably secured to said end supports, said plate being provided with dis-

dispenser throats extending therethrough in spaced relation along a longitudinal axis, said plate being also provided with vertically extending guides disposed in alignment with respective throats for maintaining stacks of containers in register therewith, two series each comprising a plurality of dispenser segments individually pivotally mounted adjacent their outer ends on said rails for angular movement in a horizontal plane and provided on their inner ends with arcuate cam portions, the segments of one series being disposed opposite the segments of the other series to provide pairs of segments whose cam portions when moved about their pivotal axes move across the opposite edges of respectively cooperating throats to thereby engage the lowermost containers of stacks disposed in said throats, a pair of substantially parallel longitudinally extending drive links pivotally connected respectively to the dispensing segments of said two series, a pair of bell cranks journaled about fixed axes and carried by said respective rails for adjustable movement therewith, corresponding free ends of said cranks being pivotally connected respectively to said drive links, and a common actuating rod operatively connected to the other corresponding ends of said crank including means for adjusting said connection in accordance with the lateral spacing of said rails, whereby a linear series of containers may be dispensed simultaneously by actuation of said rod.

4. In a dispensing mechanism for delivering a plurality of containers simultaneously, the combination of a supporting frame, two series of dispensing members pivotally mounted for movement about vertical axes disposed along respective substantially parallel longitudinal lines for angular movement in a horizontal direction, corresponding dispensing members of said series be-

ing oppositely disposed to provide a plurality of pairs spaced apart longitudinally, each pair having inwardly disposed receptacle engaging cam portions spaced apart laterally for operative engagement with opposite sides of receptacles to be dispensed, a pair of longitudinally extending laterally adjustable members supporting said two series of dispensing members respectively, to thereby vary the lateral spacing between cooperating dispensing members of said pairs, said pairs of dispensing members corresponding in number to the number of receptacles to be dispensed during each operating cycle, a pair of substantially parallel longitudinally extending drive links pivotally connected respectively to the dispensing members of said two series, and a common actuating member operatively connected to said pair of drive links for effecting said angular movement, whereby upon the movement of said common train said plurality of pairs of dispensing members are simultaneously actuated, and a plurality of stack guides having feed throats disposed in vertical axial feed alignment with respectively corresponding pairs of dispenser members for positioning the lowermost receptacle of a like plurality of stacks of nested receptacles in the path of movement of said engaging cam portions.
